UNITED STATES PATENT OFFICE.

JAMES G. BROOKS, OF OMAHA, NEBRASKA.

FLOOR WAXER AND POLISHER.

Application filed June 30, 1922. Serial No. 572,070.

To all whom it may concern:

Be it known that I, JAMES G. BROOKS, a citizen of the United States, residing at Omaha, in the county of Douglas and State 5 of Nebraska, have invented certain new and useful Improvements in a Floor Waxer and Polisher, of which the following is a specification.

This invention has for its object to provide 10 a combined floor waxer and polisher of such construction that it will be convenient in use, manually, for waxing and polishing floors, will distribute the wax uniformly and without waste, and will consist of few 15 parts so that it may be conveniently manufactured. Other objects of the invention will be stated hereinafter.

The invention consists of the novel construction, combination and arrangement of 20 parts as described herein and claimed, and as illustrated in the accompanying drawing, wherein—

Fig. 1 is a partly broken, plan view of the device. Fig. 2 is a sectional view on line 25 2—2 of Fig. 1. Fig. 3 is a sectional view on line 3—3 of Fig. 1.

Referring now to the drawing for a more particular description, I provide a wax-dispensing receptacle consisting, in part of 30 a base-plate 4 having numerous apertures or perforations 5 formed therein and having upright walls *a*, said walls being provided with inwardly projecting ridges *b*; and at 35 6 is indicated a container for a supply of wax 7, its upright walls being disposed adjacent to and inwardly of the walls *a* and ridges *b*.

Numeral 8 indicates a bearing-plate adapted to be seated on the top of the wax, 40 said plate being provided with upright, parallel guides of aligning-rods 9, and it will be understood that a downward pressure applied to the plate will tend to move the wax, or a part thereof, through the apertures 45 5 of the plate 4.

Numeral 10 indicates a porous pad or fabric adapted to lie beneath the plate 4 and to engage the outer and inner sides of the walls *a* and adapted to be maintained 50 in that position by means of a spring frame or loop 11, this spring frame being of such proportions that its ends will press the pad or fabric against the ridges *b*, one of the ends of said frame or loop being provided 55 with a roller 12 to facilitate its removal or for placing it in the position described.

At 12 is indicated a cover or lid adapted to be secured to the walls of the wax-container 6, said lid being provided with apertures *c* for receiving the rods of guides 9, and 60 provided at its middle with a slot 14. Numeral 15 indicates a yoke which is slidingly mounted on the rods 9; and springs 16 are mounted on said rods between the yoke and the plate 8. Numeral 17 65 indicates a rack-bar disposed in the slot 14 of the lid, its lower end being pivotally mounted upon the yoke, as indicated at *d* (Fig. 2) midway between the ends thereof, and it will be understood that the rack-bar 70 may be moved inwardly of the lid, against the force of the springs 16, for pressing the plate 8 against the wax to cause the latter to move outwardly through the apertures 5. 75

Numeral 18 indicates a handle provided with a pair of arms 19 having pivotal mountings upon projections 20 which are provided for the opposed sides of the wax-dispensing receptacle, midway between the ends thereof.

The parts thus described constitute the 80 complete floor waxer, and by use of the handle it may be pressed downwardly and moved upon the floor to be waxed, the wax being pressed into and through the pad or fabric 10, to form a thin coating of wax 85 upon the floor.

The polisher consists of a metallic box 21 in which the floor waxer above described may be removably disposed, the bottom of said box being provided with a plate 22 90 preferably constructed of wood, said plate 22 being provided with numerous brushes 23, and in operation, after the floor has been waxed, as mentioned, the device, by use of the handle, may be moved and pressed upon the waxed floor, and this is the operation for polishing a floor.

It will thus be seen that when the device is used for waxing a floor, it is removed 100 from the box 21, the brush not being used, and during operation the pad or fabric 10 will become somewhat heated from frictional contact with the floor, which facilitates melting of the wax and passage thereof through the apertures 5, and on this account hard wax may be employed. Also during operation the degree of pressure of plate 8 upon the wax may be adjusted from time to time as may be required, by use of the rack-bar 17, in the manner described, 105 to cause a suitable quantity of wax to pass from the container 6 to the fabric or pad.

Since the pivotal mounting for the handle is equi-distant from the ends of the device, all parts of the bottom of the pad, approximately, will have uniform pressure upon a floor.

It will be understood that when the device is used as a polisher, the wax dispensing receptacle 4 and parts first described, together with the pad or cloth 10 is placed in the box 21, the rack-bar preferably being swung a limited distance in the slot 14 for a release of its teeth from the lid, to permit retraction of the springs 16, so that the wax will not be compressed. At 24 is indicated a band or buffer which is mounted on the plate 22.

While I have described construction in detail, I do not wish to be understood as limiting myself in this respect, and changes in size, form, proportion and minor details may be made, as found to be of advantage, said changes being determined by the scope of the invention as claimed.

I claim as my invention:

- 25 1. In combination, a wax dispensing receptacle consisting of a perforated base-plate having upright walls and provided inwardly of said upright walls with a wax-container, a bearing-plate provided with guides and disposed in the wax-container, springs on the guides, a yoke engaging the springs and traversed by the guides, a lid on the wax-container provided with a slot and traversed by said guides, and a rack-bar in the slot of the lid, said rack-bar being pivotally mounted on the yoke and movable for moving the bearing-plate inwardly of the wax-container, subject to the resistance of said springs.
- 30 2. In combination, a perforated base having upright walls provided on their inner sides with ridges, said perforated base being provided adjacent to and inwardly of said ridges with a wax-container, a porous, flexible pad beneath the perforated base and engaging the outer and inner sides of the upright walls of said base, a bearing-plate in the wax-container, a spring frame for pressing parts of the flexible pad against said ridges, and means for moving the bearing-plate toward the bottom or top of the wax-container.
- 35 3. In combination, a perforated base having upright walls, a porous, flexible pad beneath the perforated base and engaging

the outer and inner sides of said upright walls, a wax-container on the perforated base, a bearing-plate provided with guides and disposed in the wax-container, a yoke traversed by the guides, springs on the guides between the yoke and bearing-plate, a lid on the wax-container provided with a slot and traversed by the guides, a rack-bar in the slot of the lid having a pivotal mounting on the yoke and movable for moving the bearing-plate inwardly of the wax-container, and a spring loop between the upright walls of the perforated base and wax-container for pressing the flexible pad against the inner sides of the upright walls of said base.

4. In combination, a perforated base having upright walls, a porous, flexible pad beneath the perforated base and engaging the outer and inner sides of said upright walls, a wax-container on the perforated base, a bearing-plate in the wax-container, springs on the bearing-plate, a yoke engaging the springs, a lid on the wax-container provided with a slot, a rack-bar in the slot of the lid having a pivotal mounting on the yoke and movable for moving the bearing-plate inwardly of the wax-container, and a spring between the upright walls of the perforated base and wax-container for pressing the flexible pad against the inner sides of the upright walls of said base.

5. In combination, a perforated base having upright walls, a porous, flexible member beneath the perforated base and engaging the outer and inner sides of said upright walls, a wax-container on the perforated base, a bearing-plate in the wax-container, springs on the bearing-plate, a yoke engaging the springs, a lid on the wax-container, a rack-bar traversing the lid and pivotally mounted on the yoke and movable for moving the bearing-plate inwardly of the wax-container, and a resilient member between the upright walls of the perforated base and wax-container for pressing the porous, flexible member against the inner sides of the upright walls of said base.

In testimony whereof, I have affixed my signature in presence of two witnesses.

JAMES G. BROOKS.
